UNITED STATES PATENT OFFICE

137,522

DESIGN FOR A TOY PISTOL

Herbert U. Dernehl, Milwaukee, Wis.

Application January 20, 1944, Serial No. 112,279

Term of patent 7 years

(Cl. D34—15)

To all whom it may concern:

Be it known that I, Herbert U. Dernehl, a citizen of the United States, residing at Milwaukee, in the county of Milwaukee and State of Wisconsin, have invented a new, original, and ornamental Design for a Toy Pistol, of which the following is a specification, reference being had to the accompanying drawing, forming part thereof.

Figure 1 is a perspective view of a toy pistol taken from the rear and one side and illustrating my new design; and

Figure 2 is a perspective view thereof taken from the front and the opposite side.

I claim:

The ornamental design for a toy pistol, as shown.

HERBERT U. DERNEHL.
